ABSTRACT: A device to form a staging on a base such as the ground comprising a single upright support, a looplike member to embrace said upright support with arms on said member extending generally horizontally laterally from the upright support for engagement with a wall of a building to provide between the upright support and the building a rest for the formation of a platform.

PATENTED JUN 22 1971

3,586,128

SCAFFOLDING DEVICE

BACKGROUND OF THE INVENTION

Usually brackets are provided fitted onto the wall of a building to extend outwardly therefrom to support a staging or the staging is hung from above or erected between two ladders with some means to hold the ladders generally upright.

SUMMARY OF THE INVENTION

A scaffolding device comprising a single upright supporting leg to rest on a base with a member slidably but closely embracing the leg and having arms extending therefrom laterally of the leg to engage the wall of the building or the like providing a generally horizontal rest for planking or a platform. When the platform or planking is placed upon the lateral arms, the weight of the planking or platform thru the leverage of the arms cants the looplike embracing member upon the upright into binding relation on the upright so that there will be no sliding and thus by this cramping action secures the looplike member to the upright.

BRIEF DESCRIPTION OF THE DRAWINGS

FIG. 1 is a perspective view showing a pair of supports with a plank resting thereon;

FIG. 2 is a side view of one part of the structure shown in FIG. 1;

FIG. 3 is a top plan view of the form of the device shown in FIG. 2;

FIG. 4 is a sectional fragmental view on a larger scale of the upright support and the member embracing it;

FIG. 5 is a similar view showing a modified form;

FIG. 6 is a top plan view showing a further modification; and

FIG. 7 is a top plan partly exploded and partly sectional view.

DESCRIPTION OF THE PREFERRED EMBODIMENTS

In FIG. 1 I have shown the side 10 of a house with an uneven supporting surface 11 of ground adjacent to the wall 10 of the house. Two uprights 12 and 14 are shown in spaced relation which may be of any height, and the device which is the form of the invention is designated as 15 located upon these uprights and supporting a plank 16 between the devices 15.

The device designated generally 15 comprises a member 20 of generally looplike form, in this case being shown generally rectangular so as to embrace the generally rectangular upright support either 12 or 14. Arms 21 and 22 are secured such as by welding 23 along opposite sides 24 and 25 of the looplike member 20 and flare outwardly therefrom and are provided with ends 26 which will engage the wall of the building such as shown in FIG. 1. In some cases a bar 27 (FIG. 5) may extend between these ends to provide a broader support and prevent the arms 21 from spreading to a greater angular relation. The plane of the arms 21 and 22 forms an obtuse angle 30 between

the upright 12 and the plane of the arms 21, 22, thus giving some angularity to the upright support 12 with relation to the wall of the house. The end of this support 12 may be of any form, that being designated in this case as 31, so as to get a good grip on the ground 11, or it may be pointed to extend somewhat into the ground. The loop 20 is angled in accordance with the angularity 30 desired for the relationship between the upright support 12 and the plane of the arms as may be seen in the side view of FIG. 2, and the relationship 5 between the embracing looplike member 20 is such that there will be broad flat surfaces 33, 34 on the inside of the loop to engage and slide along the support 12. However, when the plank such as 16 is placed upon the horizontal rest 21, 22 provided by the arms, there will be a sufficient weight upon these 10 arms so as to tend to swing the ends of the arms adjacent the building downwardly, causing the inner surface of the portion 33 of the loop to dig into the upright support 12 at 36 which may be of wood or something of that nature, while the upper edge 37 of the distant part 34 of the loop 20 will likewise dig into the support 12 and thus provide a sort of cramping action 15 which will prevent the device from sliding along the upright support or leg 12. However, in addition there may be a setscrew 40 provided through the side 36 of the loop to assure that the loop will not slide along the member initially and until 20 the weight on the arms has been located thereon, or it may be that this securing will provide a holding for the device in case the fit is not exactly correct. In some cases the arms now designated as 21' and 22' as shown in FIG. 6 may be of a parallel relation, and a looplike member designated 20' may be of a 25 size to embrace a ladder instead of a smaller leg such as designated 12 or 14 in the above figures.

In some cases, for more compact packaging for shipment, the device may be made as in FIG. 7 where the loop 45 is cast with integral studs 46 thereon over which tubular arms 47 may be telescoped in assembled form or detached from the studs 30 for more compact packaging.

I claim:

1. A scaffolding device comprising a member of looplike shape and of a size to embrace an upright support, a pair of 40 arms secured to said member and extending therefrom in spaced relation with their end portions shaped to engage an upright wall and provide a generally horizontal rest for the formation of a platform, an upright support embraced by said loop member and of a size and shape to be slidable in said member closely fitting the same and at an obtuse angle to said arms, the diagonally opposite edges of said loop being sufficiently angular and sharp to enter said upright support and bind thereon, and a platform located on said arms urging the closely fitting loop member into binding relation with said 45 upright support to prevent sliding therealong.

2. A scaffolding device as in claim 1 wherein said upright support makes an obtuse angle within the under side of the plane of said arms.

3. A scaffolding device as in claim 1 wherein the arms have 55 detachable sections.
